LIQUID SEAL COMPRESSOR

James T. Cawley and Clifton M. Cawley,
Silsbee, Tex.

Application February 5, 1948, Serial No. 6,526

7 Claims. (Cl. 230—83)

1

This invention relates generally to compressors, and more particularly to a compressor in which the energy released by gas while decreasing in pressure is utilized to increase the pressure of a separate body of gas.

A primary object of this invention is to use the potential energy in highly pressurized gas to increase the pressure of a separate body of gas by interposing mechanical means between conduits carrying the different bodies of gas, this mechanical means comprising a compressor operating with the high pressure gas as a closed system on one side of a piston in the compressor, while the initially low pressure gas is in a closed system on the other side of said piston, when the compressor comprises a simple cylinder with a reciprocating piston, it being understood that valve means must be provided to synchronize the opening and closing of inlets and outlets and each end of the cylinder, and that such operation of the valves must be synchronized.

Another object of this invention is to provide improved specific means for carrying out this synchronization of valve operation.

Still another object of this invention, when the invention is applied to the oil refining industry, and whenever the gases are of such nature that a condensate is formed, is to provide means for draining off this condensate, this means comprising a device to decrease the volume of a liquid piston when such liquid piston is used in the invention.

Yet another object of this invention is to provide a compressor of the character mentioned above which will allow a substantially constant flow of the initially high pressure gas as well as of the initially lower pressure gas, this object being carried out in the embodiment of the invention in which a pair of U-tubes are used, by providing an actuating valve, along with certain other structures, which allows high pressure gas to be admitted alternatively to the two tubes.

A highly important object of this invention is to provide a compressor which is particularly well suited for use in gasoline recycling plants where the pressure of the raw gas coming from the wells is reduced for absorption and then again raised in pressure sufficiently high to allow this "dry gas" to be forced back into the oil sand in injection wells. The compressor will be operated by the energy released in the pressure reduction. At present this energy is not being utilized. The enriched gas from the wells is at relatively high pressure, ordinarily at approximate 2600 pounds per square inch. The gas must

2

be decreased in pressure before being fed to the absorber which is a device to separate the easily available gasoline from the gas by the use of absorption oil, the pressure at which this absorption process is carried out being relatively low and in the order of 1600 pounds per square inch. At the present time the dry gas from the absorber is compressed by regular compressors operated by gasoline engines to a pressure approximately 10 2750 pounds per square inch. By the use of the instant invention it has been found possible to use the wasted energy from the high pressure gas to re-compress approximately sixty three per cent of the dry gas to a pressure in the order of 15 2550 pounds per square inch. There remains only the matter of re-compressing the thirty-seven per cent of the gas to the required 2750 pounds pressure and further compression of the sixty-three per cent of the gas from 2550 pounds 20 pressure to 2750 pounds pressure. It will be obvious that a considerable saving is hereby accomplished.

And a last object to be mentioned specifically is to provide a device of this character which is 25 relatively inexpensive and completely practicable to manufacture, which is extremely simple, practically automatic and safe to use, and which will give generally efficient and durable service.

With these objects definitely in view, together 30 with several other objects of a specific character which will become apparent as this description proceeds, this invention resides in certain novel constructions, combination and arrangement of elements and portions as will be hereinafter described in the specification, particularly pointed out in the appended claims, and illustrated in the accompanying drawings which form a material part of this application, and in which:

Figure 1 is a side elevational view of this invention with the U-tubes shown in vertical section so as to disclose the arrangement of the floats and liquid pistons;

Figure 2 and Figure 3 are vertical sectional views of the upper portions of the longer legs of the U-tubes with what may be referred to hereinafter as the compressor heads carried thereby;

Figure 4 is a vertical sectional view of the actuating valve and contiguous structure including the upper ends of the shorter legs of the U-tubes;

Figure 5 is another view of the actuating valve in a second position;

Figure 6 is a view in vertical section of a modified form of compressor head and illustrating how this modified form of pressure head is utilized

with a solid piston riding upon one end of the liquid piston; and

Figure 7 is a flow diagram illustrating how this invention is adapted for use with wells, in a recycling plant in the oil refining industry. This figure indicates how raw gas is first fed through a separator to trap out any liquid which has already condensed. The gas then enters the liquid seal compressor which allows all the gas to be lowered considerably in pressure for the absorber, the liquid seal compressor re-compressing 63% of the gas. All of the gas is returned to the oil sand as indicated.

Similar characters of reference designate similar or identical elements and portions throughout the specification and throughout the several views of the drawings.

This invention contemplates provision of a pair of U-tubes 10 and 12, each having shorter legs 14 and 16 which may be integrated, and longer legs 18 and 20. Each tube is partially filled with a liquid piston 22 and 24 which may be comprised of any suitable liquid, including condensate from the gas processed by the device, and floats 26, 28, 30 and 32 are mounted in float cages 34 at each end of each U-tube.

High pressure gas is led into the device through the pipe 36 and its branch 38, under control of a master valve 40, through the actuating valve assembly 42, and exits from the actuating valve assembly through the pipe 44 controlled by the valve 46, the actuating valve assembly is represented in Figures 4 and 5 in detail.

The actuating valve includes a cylinder 48 and a plunger 50 adapted to close and open ports 52 and 54 in the high pressure head 56 secured to the ends of the shorter legs 14 and 16 of the U-tubes. A pair of check valves 58 which are hollow and apertured as at 60 are mounted to control the ports 52 and 54, and have heads 62 adapted to seat on the suitably formed high pressure head 56, the valve heads 62 being reciprocable within chambers 64 in valve head casing 66 carried by the high pressure head 56 and located within the upper ends of the shorter legs 14 and 16. It will be noted that the valve head casings 66 are apertured as at 68, ordinarily at four points, two of these apertures being illustrated in each valve head casing in Figure 4. The check valves 58 carry actuating pins 70 projecting into the shorter legs 14 and 16 for engagement by the floats 28 and 30. From the foregoing it will be clear that high pressure gas may be made to flow into and out of the said shorter legs 14 and 16 by the manipulation of the actuating valve plunger 50, means for which actuation will be described presently, and it will also be clear that the high pressure gas will be fed alternately to the shorter legs 14 and 16 and that provision for exhausting the initially high pressure gas into the low pressure gas pipe 44 has been made.

Referring now more particularly to the compressor heads 72 and 74, illustrated in Figures 2 and 3, and the valve structure carried thereby, it may be first noted that the floats 26 and 32 are adapted to actuate disc valves 76 having actuating pins 78 depending into the longer legs 18 and 20 of the U-tubes. The disc valves 76 are apertured at 80 and the disc valve casings 82 are similarly apertured at 84, so that these valves are open when in depressed position as illustrated in Figure 2, and closed when in elevated position as in Figure 3 with the valve head closing the ports 86 in compressor heads 72 and 74. The ports 86 lead through the channel 88 to branch channels

90 and 92 leading to suction valves 94 and discharge valves 96, respectively. It will be noted that the plungers of these valves are disposed on opposite sides of the valve head and that these valves are actually merely check valves and are named suction and discharge valves in order to differentiate the same from other valves in the system, the exact character of these last mentioned valves being immaterial in this application.

The compression heads 72 and 74 have each a vent valve assembly generally indicated at 98 and including a plunger 100, a removable valve head 102 and an actuating plunger 104. The actuating plunger 104 reciprocates within a channel 88 and is provided with a valve stem 106 and a coiled spring 108 compressed between the plunger 104 and an adjacent portion of each of the compressor heads 72 and 74. The plunger 100 is also spring biased as indicated at 110 and the lower portion of the plunger 100 is adapted to be engaged by the valve stem 106 and the valve 104 is raised by pressure of the remaining gas in the ends of the longer legs 18 and 20 exerted on this plunger 104 through the apertures 84, 86 after the disc valve 76 has closed the ports 86. It will thus be seen that the vent valve plunger 100 is used to open the port 114 to the port 116 at the end of the discharge stroke of the liquid piston 22 or 24, and if reference be had to Figure 1 it will be seen that vent lines 118 are connected between the ports 116 and the low pressure pipe 44. The ports 114 are connected by pipes 120 to the ports 122 in the actuator valve cylinder 48, so that gas is vented to the lower pressure pipe 44 through the vent line 118, the chamber in the valve head casing 102, through the bore 122 in the plunger 100, the lateral port 124 provided in this plunger, and the pipe 120, allowing the high pressure gas continually admitted to the ends of the actuating valve cylinder 48 to drive the plunger 50 either to the right or to the left, as indicated in Figures 5 and 4.

The structure above described in brief, comprises a complete operative assembly, and the structure to be now described is an auxiliary system adapted to control the level of the top of the lower end of the pressurized liquid piston, so that condensate from the gas admitted under high pressure through the pipes 36 and 38 will not make the system inoperative. To carry out this level control, this means includes drain pipes 124 communicating with lower end portions of the U-tubes 10 and 12. A valve 126 is inserted in each of these drain lines 124 and is operated by a piston, not shown, within a cylindrical casing 128. One end of this casing is connected by the pipe 130 to the low pressure pipe 44, so that one side of the piston in the cylindrical casing 128 is at constant low pressure. The other end of the cylindrical casing 128 is connected by the pipe 132, in each case, to the vent line 118, and a diaphragm operated valve 134 is operatively connected in each vent line 118, the diaphragm assembly casings being indicated at 136 and the diaphragms being remotely controlled, preferably hydraulically, as indicated by pipes 138, by a float mechanism, the exact detail of which is unimportant in this application, indicated at 140 and including chambers 142 connected by elbowed pipes 144 with the shorter legs 14 and 16. The float mechanisms will be arranged to retain the valves 134 in position to close either of the vent lines 118, as long as the level of the liquid piston is above a predetermined height in the shorter

legs 14 and 16. This construction, therefore, provides means for creating a differential of pressure in the pipes 130 and 132 as long as the level in the cylinder legs 14 and 16 is above this predetermined height and a valve 126 will be opened under these conditions by the action of a piston within the casing 128. It should be carefully noted that this differential in pressure can occur only after the vent valve plunger 100 has been operated at the end of the stroke of this liquid piston 22 or 24 in exhausting gas from the longer legs 18 and 20 of the U-tubes. As soon as the level of the liquid piston is lowered to the predetermined height required, the float mechanism referred to above will be actuated to open the valve 134 concerned by remote control, whereupon the tube 132 will have the pressure reduced therein to the same pressure as that in the tube 130 and the valve 126 which had been held in open position momentarily at the end of the said stroke will again be closed.

The actuating valve plunger has recesses 146 and 148, whereby the pipes 36 and 38 are selectively connected with the ports 52 and 54, while the low pressure pipe 44 is continuously connected with the recess 148 and selectively with either one of the said ports 52 and 54. The high pressure pipes 36 and 38 are each connected by pipes 150 having needle valves 152 therein, to ports 154 in either end of the actuating valve, so that gas under high pressure is admitted alternatively to the two ends of the cylinder 48 to drive the plunger 50 alternatively as to the right and to the left in Figures 4 and 5, in each case the gas at the opposite end of the plunger is exhausted through the corresponding pipe 120 through the vent valve assembly 98 to the exhaust vent line 118. Obviously when one of the valves 134 is closed and when the liquid piston of the corresponding longer leg 18 or 20 has operated the vent valve plunger 100 into the position illustrated in Figure 3, a pressure will be built up in the portion of the vent line 118 between the closed valve 134 and the vent valve, and a differential in pressure in the pipes 130 and 132 is achieved and utilized for the purpose of draining off excess fluid, as described.

The modified form of this invention in which a metal piston 156 is inserted in each of longer legs 18 and 20, taking the place of the floats 26 and 32 and float cages 34, is used when the suction pressure is considerably less than the exhaust pressure and when there is a considerable amount of condensate in the gas that is used to drive the compressor. This metal piston or non-metallic solid piston, if material other than metal is desired to be used, forms a seal between the liquid piston and the gas that is to be compressed, thereby permitting the condensate from the gas flowing through the high pressure pipes 36 and 38 to be used as the liquid piston without possibility of the relatively dry gas that is to be compressed absorbing and becoming enriched from the condensate. Furthermore, the solid piston can be so designed that it will overcome the difference in the suction pressure and the exhaust pressure, and the solid piston will prevent any possibility of the liquid piston escaping through the discharge line.

This modified form of the invention employing the solid piston 156 is illustrated in Figure 6 and it will be noted that this solid piston has sealing rings 158 and may be of considerable length and that the solid piston will rest immediately upon the upper end of the liquid piston.

The upper ends or heads 160 of the longer legs 18 and 20 will also be modified slightly, to include suction and discharge valves 162 and 164, respectively, for connection to the corresponding suction pipe 166 and discharge pipe 168 such as are shown in Figures 1 and 6. The vent valve assembly 98' is very similar in this modified form to the vent valve assembly 98 already described, the plunger 100' being actuated by the pin 106' carried by a piston 104'. The piston 104' is actuated by the continued movement of the solid piston 156 after the port closed by the outlet valve 164 has been closed by the upper end of the said solid piston, the gas enclosed in the upper portion of the head 160 being compressed to force the piston 104' upwardly as in Figure 6 to move the plunger 100' into the position shown. As before, this action allows gas under high pressure from the pipes 150 to escape from one end of the actuating piston and reverse the plunger 50. Reference to Figure 7 may be made in connection with the penultimate and the primary object of this invention, to illustrate further how this invention may be implemented. In this figure certain lines have been numbered to indicate the corresponding portions in Figure 1. The pipes leading to the intake and outlet valves 94 and 96 being numbered 166 and 168, respectively, in both figures. Compressor pipes are not shown in duplicate.

In operation, gas under pressure admitted through the actuating valve to one of the cylinder legs 14 or 16, forces the liquid piston downwardly until this same liquid piston rises in the longer legs 18 or 20 sufficiently to raise the float 26 or 32 and to actuate the disc valve 76 to close the corresponding ports 36 and 38 and pressure is still being applied to the liquid piston and the same will move still further to cause the piston 104 or 104' to raise the plunger 100 or 100' and this action allows high pressure gas from one of the pipes 150 to circulate through the end chamber of the actuating valve and through the pipe 120 into the port 114 and through the hollow plunger 100 or 100' and into the vent line 118. This vent line will be open, provided the valve 134 is not actuated as a result of the raising of the volume of the liquid piston beyond the required amount as already described in detail, and as soon as the plunger 50 is moved into its reverse position, a new charge of the gas to be compressed is allowed to feed into the longer leg 18 or 20 through the valves 94, while the gas from the high pressure pipes 36 and 38, that is, the gas in the corresponding lower leg 14 or 16, will be exhausted into the low pressure pipe 44. An exact reversal of operations will be coincident in the outer U-tube assembly, so that a substantially steady flow of gas, both that to be reduced in pressure and that to be increased in pressure, will be maintained. Thus, gas from the wells is reduced in pressure as it passes through the liquid seal compressor for processing in an absorber to remove the easily available gasoline. Energy released by this reduction in pressure is used to operate the liquid seal compressor which raises approximately 63% of the original gas to a pressure nearly equal to the original gas pressure. The other 37%, as well as the above mentioned 63%, must be further raised in pressure if the same is to be used for re-pressuring the oil field, but it will be clear that this invention lessens the amount of power required to be provided by independently driven pumps.

Minor variations in the details of construc-

tion, and proportionment of the various elements of this invention may be resorted to without departure from the spirit and scope of this invention. The drawings, particularly, should be thought of as illustrative rather than limiting and the scope of the invention should be determined only in accordance with a proper interpretation of the terminology used in the subjoined claims.

Having described the invention, what is claimed as new is:

1. A compressor comprising a cylinder, a sealing piston in said cylinder, an inlet for initially high pressure gas and an outlet for lowered pressure gas at one end of the cylinder, an inlet 15 for initially low pressure gas and an outlet for gas raised to an intermediate pressure on the other end of said cylinder, valves controlling each of said inlets and outlets, and means for synchronizing the opening and closing of the first mentioned inlet and the second mentioned outlet with the closing and opening respectively of the first mentioned outlet and the second mentioned inlet, whereby the energy released by said initially high pressure gas in decreasing in pressure is utilized, in part, to increase the pressure of said initially low pressure gas.

2. A compressor comprising a U-tube, a liquid piston in said U-tube, an inlet for initially high pressure gas and an outlet for lowered pressure gas at one end of the U-tube, an inlet for initially low pressure gas and an outlet for gas raised to an intermediate pressure on the other end of said U-tube, valves controlling each of said inlets and outlets, and means for synchronizing the opening and closing of the first mentioned inlet and the second mentioned outlet with the closing and opening respectively of the first mentioned outlet and the second mentioned inlet, whereby the energy released by said initially high pressure gas in decreasing in pressure is utilized, in part, to increase the pressure of said initially low pressure gas.

3. A compressor comprising a U-tube, a liquid piston in said U-tube, an inlet for initially high pressure gas and an outlet for lowered pressure gas at one end of the U-tube, an inlet for initially low pressure gas and an outlet for gas raised to an intermediate pressure on the other end of said U-tube, valves controlling each of said inlets and outlets, and means for synchronizing the opening and closing of the first mentioned inlet and the second mentioned outlet with the closing and opening respectively of the first mentioned outlet and the second mentioned inlet, whereby the energy released by said initially

high pressure gas in decreasing in pressure is utilized, in part, to increase the pressure of said initially low pressure gas, said liquid piston having a solid sealing piston at one end thereof and movable therewith.

4. A compressor comprising a U-tube, a liquid piston in said U-tube, an inlet for initially high pressure gas and an outlet for lowered pressure gas at one end of the U-tube, an inlet for initially low pressure gas and an outlet for gas raised to an intermediate pressure on the other end of said U-tube, valves controlling each of said inlets and outlets, and means for synchronizing the opening and closing of the first mentioned inlet and the second mentioned outlet with the closing and opening respectively of the first mentioned outlet and the second mentioned inlet, whereby the energy released by said initially high pressure gas in decreasing in pressure is utilized, in part, to increase the pressure of said initially low pressure gas, said means including a vent valve operated by said piston and an actuating valve having a plunger and spaced ports, said vent valve controlling flow of gas under pressure to said ports and actuating said plunger to open and close said first mentioned inlet and outlet.

5. A compressor according to claim 4 and including another U-tube having a similar complement of inlets, outlets, valves and means, said plunger and ports opening and closing the first mentioned inlet and outlet in the different U-tubes alternately, so that a substantially constant flow of both said initially high and initially low pressure gas is achieved.

6. A compressor according to claim 5 and including check valves on said one end of the first mentioned U-tube and a corresponding end of the second mentioned U-tube, and a float moving said check valves.

7. A compressor according to claim 5 and including means to drain off a portion of said fluid piston when the volume thereof is increased as by absorption of condensate.
